UNITED STATES PATENT OFFICE.

ALBERT B. HERRICK, OF CLEVELAND, OHIO, ASSIGNOR TO THE ELECTRIC RAILWAY IMPROVEMENT COMPANY, OF CLEVELAND, OHIO, A CORPORATION OF OHIO.

CAR FOR BONDING RAILS.

No. 906,021.

Specification of Letters Patent.

Patented Dec. 8, 1908.

Application filed March 25, 1905. Serial No. 252,095.

To all whom it may concern:

Be it known that I, ALBERT B. HERRICK, a citizen of the United States, resident of Cleveland, county of Cuyahoga, and State of Ohio, have invented a new and useful Improvement in Cars for Bonding Rails, of which the following is a specification, the principle of the invention being herein explained and the best mode in which I have contemplated applying that principle, so as to distinguish it from other inventions.

My invention relates to car structures, and particularly to a car structure adapted for use in connection with operations to be performed upon the rails of car-tracks, such as rail-bonding, joint-testing, and the like, as described in my application for Letters Patent, Serial No. 237,353, filed December 17, 1904.

20 The object of this invention is to effect such operations in an efficient and economical manner, said invention consisting of means hereinafter fully described and particularly set forth in the claims.

25 The annexed drawings and the following description set forth in detail certain mechanism embodying the invention, such disclosed means constituting but one of various mechanical forms in which the principle 30 of the invention may be used.

In said annexed drawings:—Figure 1 represents a vertical longitudinal central cross-section of that part of a car embodying my invention, the air-compressor and reservoir being shown therein in elevation, and one of the air-cylinders cut by the plane of section being shown in vertical section. Fig. 2 represents a horizontal section of the car showing the bottom thereof in plan, the air-compressor being however omitted from this view for convenience, this view being taken upon the plane indicated by line 2—2, Fig. 1. Fig. 3 represents a vertical transverse section taken upon the plane indicated by line 3—3, Fig. 1. Figs. 4, 5, 6, and 7, represent a detailed plan elevation of sections of portions of the mechanism on an enlarged scale.

The car-body A embodied in the structure 50 is provided with a single truck A' which supports a car-frame, as shown in Fig. 1. Such frame includes two sills a a upon which is laid the flooring a', the latter being formed with a central rectangular opening x²,

forming an open space between the bolsters 55 a³ a³ and the wheels a⁴ a⁴ of the truck. Braces a⁵ a⁵ support the ends of the sills, the truck forming the struts which complete trusses for the car, as will be readily understood. Having its ends resting upon the 60 central part of the sills a a is an arch A², preferably constructed of channel steel. This arch is preferably made so as to form a support for the central part of the roof a⁶, as described in said above-mentioned 65 application and forming support for other parts of the mechanism which, however, forms no part of this present invention.

Secured to the sides of the car by means of suitable brackets h, Figs. 1 and 3, are four 70 air-cylinders h' and cooperating pistons h² therefor. These cylinders are connected by means of suitable pipes h³ with a reservoir H', as shown, whereby compressed air may be admitted above the pistons by means of a 75 suitable cock h⁷. An air-compressor H is suitably connected with the reservoir for supplying the same with the required compressed air. The pistons operate vertically and there is secured to the lower end of each 80 piston a rod and depending carrier rod h⁴ to the lower ends of which latter is attached a horizontal platform J, the latter being normally located a short distance above the rails of the track. This platform is held in 85 such normal position, that is, the position in which the pistons are located in the upper portions of the cylinders by means of helical springs h⁵ which are attached to yokes h⁶ secured to the upper ends of the rods h⁴, as 90 shown. These springs are suspended from the sides of the car by threaded rods a¹⁰ supported in brackets a⁹, suitable nuts a¹¹ being provided for adjusting the tension of the springs as will be readily understood. It 95 will therefore be seen that when the compressed air is admitted above the pistons the platform will be actuated downwardly toward the track and when such pressure is withdrawn the springs will act to return it to 100 its normal position, a suitable relief valve (not shown) being provided in each cylinder, as will be readily understood, to permit of the unobstructed upward movement of the pistons. Cut in the platform immediately 105 above the two rails respectively of the track are two openings j j, Fig. 2, which permit the operator to have access to the rails from the

interior or the car for the purpose of performing the desired operations upon such rails.

Upon the bottom of the platform are secured members for effecting frictional contact with the rails. These members consist in the structure illustrated, of brake-shoes K for stopping the car and contact brushes K' for making contact for the electrical recording device for indicating and recording the electrical condition of the rails, such as is shown and described in pending application, Serial No. 209,115, filed May 21, 1904. The contact brushes are, as shown in Fig. 4, mounted so as to normally be in a plane below the brake-shoes, so that they may be caused to engage the rails while the brake-shoes are out of contact therewith. Such arrangement permits the recording device to be used without bringing the brakes into play. By employing the automatic cut-out device, shown and described in the pending application, Serial No. 209,116, filed May 21, 1904, the braking of the car, that is, the downward action of the platform may be controlled automatically by the recording instrument, that is, whenever the voltage at the rail-joint rises above a certain point the car may be automatically stopped. In such case the cock h⁷ would be automatically controlled.

Attached to the front and rear ends respectively of the platform J, by means of flexible leather connections j', are two guard-plates J' J' which project upwardly into the central opening in the floor, as shown in Fig. 1, the upper ends of such plates resting against the front and rear edges of such opening. These edges are extended downwardly by means of transverse boards a¹² a¹² which, together with the extremities of the flooring form a support against which the upper ends of said guard-plates rest during the upward and downward movement thereof. These plates are bent forwardly and backwardly respectively as shown, so that their normal position will be maintained by gravity. Apertures j² j² are formed therein for receiving the wheels a⁴. It will therefore be seen that the openings between the platform and flooring are closed by these plates thus protecting the operator, and in conjunction with the sides of the car substantially inclosing the entire operating space on all four sides.

The front and rear ends of the platform are connected directly with the wheel-truck frame by means of links l whose inner ends are pivoted to the platform as shown in Figs. 4 and 5. The outer ends of these links are connected to the lower ends of the hangers A⁸ A⁸ of the trucks by means of pins a¹³ a¹³ suitably secured thereto. These pins pass through elongated openings l' respectively, formed in the outer ends of these links, and

when the platform is in its normal position engage the inner ends of these openings, as shown in Fig. 1, so that when in this position the platform is loosely connected with the truck. When however, the platform is lowered and the brake-shoes are resting upon the rails the pins engage the opposite ends of the openings so that in this position the platform is fixed relatively to the truck, and the longitudinal strain due to the frictional contact between the brake-shoes and rail, when the car is in motion, is transmitted to the truck, thus entirely relieving the rods h⁴ from such strain. 75

It will therefore be seen from the above 80 construction that the workman may remain in the operating space formed by the platform, raise and lower the latter as desired and perform various operations upon the rails with convenience and safety. 85

Having described my invention in detail, that, which I particularly point out and distinctly claim, is:

1. In apparatus for bonding rails, the combination with a carriage adapted to be transported along a track, of a platform supported from said carriage in the vicinity of the track and provided with openings above the track rails respectively. 90

2. In apparatus for bonding rails, the combination of a carriage adapted to be transported along a track, a platform suspended resiliently from said carriage, and means for moving said platform in vertical planes. 95

3. In apparatus for bonding rails, the combination of a carriage adapted to be transported along a track, a horizontal platform suspended from said carriage in the vicinity of the track-rails, means for raising and lowering said platform, and members secured to the latter and adapted to afford electrical contact with the rails when said platform is lowered. 100

4. In apparatus for bonding rails, the combination of a carriage adapted to be transported along a track, a platform suspended from said carriage, means for raising and lowering said platform, means connecting the latter directly with the car trucks, said platform provided with contact members secured to the platform for making contact with the rails when the platform is lowered. 110

5. In apparatus for bonding rails, the combination of a carriage adapted to be transported along a track, and having an opening in its floor, a platform suspended from the car and below said opening, two guard members secured to the front and rear of said platform respectively and extending upwardly to the front and rear of said opening respectively, and means for raising and lowering said platform and attached guard members. 120

6. In apparatus for bonding rails, the combination of a carriage adapted to be trans- 125

pointed along a track, and having an opening in its floor, a platform suspended from said carriage below such opening, two guard members flexibly secured to the front and rear of said platform respectively and extending upwardly to the front and rear of said opening, respectively, and means for raising said platform and attached guard members.

10 7. In apparatus for bonding rails, the combination of a carriage adapted to be transported along a track, a platform suspended from said carriage, means for raising and lowering said platform, and means adapted 15 to loosely connect said platform to said carriage when raised and to hold the same longitudinally fixed relatively to said carriage when lowered.

8. In apparatus for bonding rails, the combination of a carriage adapted to be transported along a track, a platform suspended from said carriage, means for raising and lowering said platform, and means adapted 25 to loosely connect said platform to the trucks of said carriage when said platform is raised and to hold the same longitudinally fixed relatively thereto when lowered.

9. In apparatus for bonding rails, the combination of a carriage adapted to be transported along a track, a platform suspended 30 from said carriage, means for raising and lowering said platform, and links connecting said platform with the trucks of said carriage, such links being provided with elongated openings and being so disposed as to make such connection a loose one when said platform is raised and a rigid one when the same is lowered.

10. In apparatus for bonding rails, the combination of a carriage adapted to be transported along a track, a platform suspended 40 from said carriage, means for raising and lowering said platform, said platform being provided with contact members adapted 45 to engage the track rails and to afford electrical contact therewith when the platform is lowered, and means connecting said

platform with the car independently of the suspending means.

11. In apparatus for bonding rails, the combination of a carriage adapted to be transported along a track, a platform suspended from said carriage, means for raising and lowering the platform, the latter being provided with contact members adapted to 55 frictionally engage the track rails, means connecting said platform with the car independently of the suspending means, and two upright guard members secured to the said platform at the ends thereof respectively, said guard members being attached to said platform by means of flexible connections.

12. In apparatus for bonding rails, the combination of a car, a plurality of resiliently-supported vertically-disposed rods, a platform suspended by said rods below the car floor, pressure-operated means for actuating said rods, and means for manually controlling such pressure-operated means. 60

13. In apparatus for bonding rails, the combination of a car, depending retractile supporting means mounted upon the car, a platform suspended from said supports, and pressure operated means for actuating said 75 supporting means against the action of the retractile element thereof.

14. In apparatus for bonding rails, the combination of a car, a plurality of pressure cylinders and pistons therefor mounted upon 80 said car, depending rods respectively connected with said cylinders, a platform suspended from said rods, and springs connected with said rods and having one end fixed to said car, said pistons being adapted 85 to actuate the platform downwardly, and said springs being arranged to operate in opposition to such downward movement.

Signed by me, this 22nd day of March 1905.

ALBERT B. HERRICK.
